UNITED STATES PATENT OFFICE.

JOHN B. WALKER, OF BIRMINGHAM, ALABAMA.

PROCESS FOR DRYING SAND MOLDS.

1,299,522.

Specification of Letters Patent. Patented Apr. 8, 1919.

Application filed August 4, 1917. Serial No. 184,468.

To all whom it may concern:

Be it known that I, JOHN B. WALKER, a citizen of the United States of America, residing at Birmingham, in the county of Jefferson and State of Alabama, have invented certain new and useful Improvements in Processes for Drying Sand Molds, of which the following is a specification.

My present invention relates to a process for drying or baking the sand molds of the type used for casting large hollow articles such as ingot molds, heavy pipe and the like and in which a sand cheek and core are provided.

The principles underlying my invention will be understood by a description thereof as applied to the baking of sand molds in which ingot molds are cast, such molds comprising a flask having a sand cheek formed therein, a core arbor having a sand core formed thereabout, and a stool drag upon which the flask and arbor are mounted. Such an arrangement is generally described in my Letters Patent of the United States, No. 1,151,229, issued to me August 24th, 1915, by reference to which it will be seen that my preferred manner of ramming the cheek and core is by means of a jolt machine or jarring table which forms both cheek and core simultaneously, though my present invention is not concerned with the manner in which the sand is rammed to form the cheek and core but rather with the manner in which the flask and core are handled in order to dry or bake the sand. Heretofore the practice has been to provide an oven in which the cheek and core were baked in accordance with the practice well understood in this art. Such ovens are costly to construct and the maintenance and heating of the oven, the careful handling necessary for the cheek and core, and the warping of the flask and core arbor resulting from the oven heat, all constitute a considerable part of the production cost of the castings.

The object of my present invention is to devise a process by means of which the core and cheek can be baked at a minimum expense and without requiring the construction or maintenance of a baking oven, thereby permitting the drying process to take place at such point as is convenient in the foundry and without appreciable expense for labor, maintenance or equipment, and without delay in closing the mold after the cheek and core are baked.

According to my process, the cheek and core after the ramming operation and after being stripped from the pattern, are reassembled so that the mold cavity formed therein will constitute a flue having a bottom air inlet through which a gas coil or pipe is passed preferably conforming in shape to the cross section of the mold cavity and designed to cause heated gases to flow up through the flue as formed between the core and cheek sand and to effectually dry the mold. Preferably the hot gases are produced by the combustion of gas at the base of the flue, the pipe serving in this instance as a burner, but obviously hot gas or air may be introduced from any suitable source where such an arrangement is more economical.

As illustrative of an apparatus for carrying my process into effect, reference is made to the accompanying drawings, in which:

Figure 1 presents a cross-sectional view taken on the horizontal plane 1—1 through an assembled sand mold adapted for the casting of ingot molds.

Fig. 2 is a vertical section on the line 2—2 of Fig. 1.

Similar reference numerals refer to similar parts throughout the drawings. 85

In the apparatus illustrated, I show a stool drag 1 having a metallic core arbor 2 mounted thereon and adapted to receive a sand core 3. A flask 4 is shown formed in vertical half sections but its particular construction is not material except that provision should be made for connecting to its bottom edge 5 by a clamp 6 a stripping plate 7 which is adapted to be lifted off of the stool drag with the flask when the cheek is stripped from the pattern. The sand forming the cheek 8 is supported beneath by the stripping plate when the flask is lifted clear of the stool drag. Assuming that the core and cheek have been rammed about the pattern in any desired manner and both core and cheek stripped from the pattern, we are now ready to proceed with the steps incident to the practice of my baking process, according to which the flask with the contained cheek is lowered back over the core and seated upon blocks 9 which support the flask sufficiently above the stool to permit the free access of air to the bottom of the mold cavity and also the introduction of a gas pipe 10. This pipe 10 preferably is bent to a shape corresponding substantially with the
